Horace Barnes
ATTORNEY

UNITED STATES PATENT OFFICE.

MASON EDWIN CLARK, OF SEATTLE, WASHINGTON.

DEVICE FOR LAYING OUT PIPE-FLANGES.

1,314,184.

Specification of Letters Patent. Patented Aug. 26, 1919.

Application filed May 27, 1918. Serial No. 236,749.

To all whom it may concern:

Be it known that I, MASON EDWIN CLARK, a citizen of the United States, and resident of Seattle, in the county of King and State 5 of Washington, have invented certain new and useful Improvements in Devices for Laying Out Pipe-Flanges, of which the following is a clear and exact specification.

This invention relates to improvements in 10 tools or instruments for locating and marking the centers of holes that are to be drilled in pipe flanges and the object of this improvement is to provide a strong and relatively simple and easily operated device of 15 this nature with which the holes in pipe flanges may be marked out with great rapidity.

A further and more specific object is to 20 provide a device of this nature that is constructed so that it will operate with great accuracy and at the same time is strong enough so that one of its parts may be struck a relatively hard blow to cause it to make a mark like a punch mark to indicate the 25 center of the hole that is to be drilled.

A still further object is to provide a device of this nature that embodies novel, 30 efficient and easily operated means for centering the device within the central opening in a pipe flange.

The invention consists in the novel construction, adaptation and combination of parts, as will be more clearly hereinafter described and claimed.

35 In the accompanying drawings, Figure 1 is a plan view of a device constructed in accordance with this invention; Fig. 2 is a view in vertical section substantially on broken line 2-2 of Fig. 1, certain parts 40 being broken away and certain other parts being shown in elevation; Fig. 3 is a view in cross section on broken line 3-3 of Fig. 2 showing the parts as they would appear if the plug that projects downwardly into 45 the top end of the hollow shank was removed; Fig. 4 is a view in cross section on broken line 4-4 of Fig. 2; Fig. 5 is a view in cross section on broken line 5-5 of Fig. 2; Fig. 6 is a detached view in perspective of 50 one of the centering devices as it may appear when extended to fit a pipe flange having a large central opening and Fig. 7 is a view in longitudinal section of a marking tool that is adapted to be used in connection 55 with this device.

In locating and marking the centers of

holes that are to be drilled in pipe flanges when the pitch diameter and number of holes required are known it is common practice to plug the central opening of the flange 60 with a piece of wood or similar material, find the center of this plug with a pair of dividers, then describe a circle of the given diameter and then by a cut and try method to space off the required number of holes. 65 After the centers of the holes are located they are usually marked by an indentation with a prick punch, a small circle is then described to indicate the circumference of the desired hole and five or six prick punch 70 marks are made at spaced intervals around the small circle to guide the driller.

The above method when accurately carried out requires the expenditure of considerable time on each flange. 75

The device disclosed in this application enables a person to perform the work of laying out the holes on a pipe flange at a great saving of time as compared to the old method and is accurate and reliable in 80 operation.

Like reference numerals designate like parts throughout the several views of the accompanying drawings.

Referring to the drawings the numeral 85 10 designates a tubular shank that is provided near its top end with an annular flange 11 and above the flange with an external thread 12 that is adapted to screw upwardly 90 through a plate 13 and through the bottom of a concentrically arranged shallow dish-shaped member 14, the flange 11 engaging with the bottom of the plate 13 and serving as a stop.

The member 14 is provided with relatively shallow vertically arranged cylindrical side walls 15 in the top edge of which are provided a plurality of notches 16 that are marked or graduated as shown in Fig. 1 to indicate the number of holes that are 100 to be drilled in the flange. 95

Fixedly secured within the top end of the shank 10 is a plug 17 having a concentric bore to permit the passage of a stem 18 and provided on its top end with a concentrically arranged upwardly directed bearing shank or sleeve 20 that is externally threaded at its top end for the reception of a nut 21. 105

22 is a collar that is journaled on the shank 20 and is connected by a pivot 23 with members 24 that are fixedly secured by 110

screws or rivets 25 to the inner end of a graduated measuring arm 26, the arrangement being such that the outer end of the measuring arm may be lifted up and the 5 arm rotated or turned about the central axis of the device.

The arm 26 is substantially T-shape in cross section the horizontal portion having the graduations inscribed thereon and the 10 vertical portion being adapted to fit snugly within the notches 16.

Slidable on the arm 26 is a marking device 27 that is provided on its bottom end with a removable centrally arranged punch member 28 and on its top end with a knob 30 that serves as a finger hold and that may be struck with a heavy instrument, as a mallet, to cause the punch member 28 to make an indentation.

20 The marking device 27 is adjustably secured to the measuring arm 26 by a thumb screw 31 as more clearly shown in Fig. 5 and such marking device is provided with a curved edge 29 that is adapted to be set on the curved graduation on the arm 26 that marks the desired diameter. The edge 29 may be notched as at 29' to facilitate setting it exactly on the desired graduation.

The plate 13 is secured to the member 14 30 by screws 32 and is provided at intervals with outwardly projecting arms 33 that are flush with the bottom of the plate 13 and serve to support the device in the correct position on a pipe flange 34 while it is being 35 centered.

The centering devices comprise three arcuate members 35, 36, and 37 that are adapted to move into and out of the shank 10 through guide slots 38.

40 The lower ends of the members 35, 36 and 37 are connected by pivots 40 with a disk 41 that is adapted to be moved vertically in the shank 10 by the threaded bottom end 42 of the stem 18 which extends therethrough.

45 The top surface of the disk 41 is recessed as at 43 to facilitate the securing of the lower ends of the arcuate arms thereto and the shank 10 may be perforated as at 44, see Fig. 4, to permit the insertion of the pivot 50 screws 40 when the device is assembled.

The bottom end of the plug 17 is slotted at three points around its peripheral edge as indicated at 45 to form guides for the outwardly projecting ends of the centering members 35, 36 and 37.

55 The centering members 35, 36 and 37 are disposed and arranged as shown in Figs. 2, 3 and 4 so that they may be withdrawn entirely within the shank 10 and when in such 60 position will not interfere with each other or with the screw 42.

The centering members are all of the same length and when the disk 41 is raised by rotating the screw 42 such members will 65 at all times be projected an even distance

from the axis of the device, and will engage the interior wall of a pipe flange as indicated by dotted lines 34' of Fig. 3 at three points about its circumference thereby serving to accurately center the device within 70 the central opening of the pipe flange.

The centering members 35, 36 and 37 are each provided at their outer ends with folding extensions 46 that are secured thereto by screws 47 and are adapted to be turned 75 outwardly into the position shown in Fig. 6 to permit the device to be centered in a flange having a central opening that is too large to be reached by the members 35, 36 and 37 without the use of the extensions. 80

The stem 18 is provided at points below the plug 17 and above the nut 21 with fixed collars 48 and 49 respectively that serve to prevent vertical movement thereof and is further provided on its top end with a fixed 85 mounted hand wheel 50 by which it may be turned.

When a pipe flange 34 is to be marked out the shank 10 is inserted in the central opening 34' of the flange and the plate 13 and 90 arms 33 are permitted to rest on the top of the flange.

The screw 42 is then rotated by turning the hand wheel 50 to expand the centering members 35, 36 and 37 against the inner 95 annular wall of the central opening of the flange thereby securing the instrument in a central location with respect to the pipe flange.

The marking device 27 is then set so that 100 the edge 29 registers exactly with the graduation indicating the desired pitch diameter of the holes that are to be placed in the notch 16' as shown in Fig. 1 which constitutes an initial or starting point. The marking device is then struck a blow sufficiently hard to cause the punch member 28 to make an indentation or punch mark on the pipe flange at the point where the hole is to be. 105

The arm 26 is then lifted and successively 110 positioned in the notches 16 indicating the other points that are to be marked and the striking operation repeated: For instance if six holes are to be marked out on a pitch circle five inches in diameter the marking 115 device 27 is set on the five inch graduation mark, as shown in Fig. 1, and the arm 26 is first placed in the initial or starting notch 16' and struck with a mallet and then is successively placed in the notches indicated 120 by the small numerals "6" on the top of the flange and struck with a mallet to mark the centers indicated at the points 51 in Fig. 1.

It will be seen from an inspection of Fig. 2 that when the arm 26 is in a notch 16 and 125 the point of the punch member 28 is resting on the flange there is a clearance between the bottom of the notch and the bottom of the vertical flange of the arm 26 so that when the member 27 is struck with a mallet the 130

force of the blow will not tend to bend the arm 26.

It is obvious that this device may be made in various sizes and that any number of notches 16 may be provided but it has been found in practice that the device shown in the drawings, which provides for the laying out of any number of holes from four to ten inclusive on any pitch diameter from four to fourteen inches is sufficient to satisfy all ordinary requirements.

In Fig. 7 I have shown a tool for quickly and easily making a number of indentations or punch marks 52 on the circumferential line 53 of a hole that is to be bored as indicated in Fig. 1.

This device comprises a body member 54 having an enlarged bottom end 55 that is provided with a plurality of diametrically arranged punch points 56 and having a rounded top end that may be struck with a mallet.

The body portion 54 is provided with an axial bore 57 extending from the enlarged bottom end inwardly and adapted for the reception of a centering pin 58 that bears against a compression spring 60 and is provided with a slot 61 on one side for the reception of a screw 62 that limits the outward movement of the centering pin.

The marks 52 are made by placing the point of the pin 58 in one of the punch marks 51 pressing downwardly until the points 56 rest on the surface of the flange 34 and then striking a blow on the rounded top end of the member 54.

It will be understood that changes in the form of construction and arrangement of the various parts of this device may be made within the scope of the following claims.

What I claim and desire to protect by Letters Patent is—

1. A device of the class described comprising a shank, means associated with said shank for centering it within a cylindrical opening, a graduated arm pivoted for tilting movement and for movement around the axis of said shank, an annular notched flange supported by said shank for determining the angular position of said arm and a marking device carried by said arm.

2. A device of the class described comprising a shank, means for centering said shank within a cylindrical opening, a disk concentrically secured to the top end of said shank, said disk having upwardly projecting cylindrical sidewalls, there being a plurality of notches in the top edge of said sidewalls, a graduated measuring arm rotatable about the central axis of said shank, and adapted to be positioned within said notches, and a marking device movable lengthwise on said measuring arm.

3. A device for laying out holes on a pipe flange comprising a shank, means for center-

ing said shank within a cylindrical opening in said pipe flange, a plate secured on the top end of said shank, outwardly projecting arms fixedly connected with said plate and flush with the bottom surface thereof, said arms and said plate being adapted to rest upon the top surface of a pipe flange, a cylindrical receptacle secured to said shank above said plate, said cylindrical receptacle having vertical sidewalls that are provided in their top edge with notches arranged in graduated relation with respect to each other, a measuring arm pivotally mounted for vertical movement at its inner end and rotatable about the axis of said shank in a plane at right angles thereto, said measuring arm being adapted to be selectively positioned within said notches, and a marking device movable lengthwise of said measuring arm.

4. A device for laying out holes on a pipe flange comprising a shank, means for centering said shank within the central opening of said pipe flange, supporting means secured to the top end of said shank and adapted to rest upon the top of said pipe flange, a measuring arm pivoted at its inner end for tilting movement in the plane of the axis of said shank and rotatable about the axis of said shank in a plane at right angles thereto, means for determining the angular position of said measuring arm, and a marking device movable lengthwise on said measuring arm.

5. A device for laying out holes on a pipe flange comprising a shank, means for centering said shank within the central opening of a pipe flange, a measuring arm tiltably secured at its inner end to said shank and rotatable about the axis of said shank in a plane at right angles thereto, a marking device movable lengthwise of said measuring arm, and supporting means secured to the top end of said shank and adapted to rest on the top of a pipe flange, said supporting means having notches therein for the reception of said measuring arm whereby said measuring arm may be moved through a predetermined angle about said shank.

6. A device for laying out holes on a pipe flange comprising a shank, means for centering said shank within the central opening of a pipe flange, a measuring arm tiltably secured at its inner end to said shank and rotatable about the axis of said shank in a plane at right angles thereto, a marking device movable lengthwise of said measuring arm, and supporting means rigidly connected with the top end of said shank for engaging with the top side of a pipe flange, the top side of said supporting means being graduated with a plurality of notches in which said measuring arm may be selectively placed to space off a desired number of equidistant points on a given diameter.

7. A device of the class described comprising a tubular shank having a plurality of guide slots therein, a graduated measuring arm mounted for rotation about the axis of said shank at the top end thereof, a plurality of arcuate centering members movable into and out of said shank through said guide slots to center said shank within a cylindrical opening and means for moving 10 said centering members.

8. A device of the class described comprising a tubular shank having a plurality of guide slots therein, a graduated measuring arm tiltably secured to the top end of 15 said shank and rotatable about the axis of said shank in a plane at right angles thereto, a disk movable within said shank, a threaded stem disposed axially of said shank and extending through said disk for moving the 20 disk vertically within the shank, and three arcuate centering members all pivoted at their bottom ends to said disk and movable into and out of said shank through said 25 guide slots to center said shank within a cylindrical opening.

9. A device for marking out pipe flanges comprising a tubular shank having a plurality of slots therein, a fixed plug disposed within the top ends of said shank and having a concentric sleeve that projects above 30 the top of said shank, said plug also having a concentrically arranged bore, a stem disposed within said bore, said stem having a threaded lower end, a hand wheel fixedly se-

cured on the top end of said stem, a disk 35 threaded on said stem and movable vertically within said tubular shank in response to rotation of said stem, a plurality of arcuate centering members pivotally secured at their bottom ends to said disk and projecting 40 upwardly and outwardly through said slots in said shank whereby when said disk is raised within said shank said centering members will be expanded against the inner walls of the central opening of pipe flange 45 and secure said shank in concentric relation within said central opening, a plate secured to the top end of said shank and provided with outwardly projecting arms that are flush with the bottom surface thereof, a cylindrical receptacle secured to said plate in concentric relation to said shank, said cylindrical receptacle having a plurality of notches in its top edge that are graduated 50 with respect to each other, a collar rotatably mounted on the upwardly projecting sleeve of said plug, a graduated measuring arm pivotally secured to said collar whereby it may be tilted into and out of said notches and rotated about said sleeve, said measuring 55 arm being adapted to fit within said notches whereby its angular position may be determined, and a marking device movable lengthwise of said measuring arm.

Signed at Seattle, Washington, this 12th 60 day of April, 1918.

MASON EDWIN CLARK.
